DESIGN FOR A LAMP

Allan Moore, Sacramento, Calif.

Application July 2, 1945, Serial No. 120,463

Term of patent 3½ years

(Cl. D48—20)

To all whom it may concern:

Be it known that I, Allan Moore, a citizen of the United States, residing at Burbank, Los Angeles County, California, have invented a new, original, and ornamental Design for a Lamp, of which the following is a specification, reference being had to the accompanying drawing, forming part thereof.

Referring to the drawing:

Figure 1 is a perspective view of a lamp, showing my new design; and

Figure 2 is a transverse section taken as indicated by line 2—2 of Figure 1.

The characteristic feature of my design for a lamp resides in the lamp shade with the surface ornamentation thereon in combination with the lamp standard shown.

I claim:

The ornamental design for a lamp, as shown and described.

ALLAN MOORE.
